VALVE GRINDER

Application filed May 9, 1930. Serial No. 451,040.

Our invention relates to valve grinders and our object is to provide a simple, inexpensive and efficient device of this character including a vacuum cup for rotating and lifting the 5 valve, and a centering element for centering said vacuum cup upon the valve.

By providing a vacuum cup the valve may be rotated and lifted from time to time to change its general position on the seat without using the spring generally employed for that purpose, and by providing the centering element the vacuum cup is centered upon and prevented from slipping sidewise off the valve.

15 In order that the invention may be fully understood, reference will now be had to the accompanying drawing, in which:

Fig. 1 is a broken side elevation, partly in section of the tool in position for grinding a 20 valve.

Fig. 2 is an inverted plan view of the valve.

Fig. 3 is a detail perspective view of a centering device employed in carrying out the invention.

25 Fig. 4 is a broken detail perspective view of the vacuum cup and the stem to which it is connected.

Referring in detail to the different parts, 2 designates a shank of suitable length which 30 is provided at its upper end with a handle 4 and at its lower end with a vacuum cup 6. The vacuum cup 6 is made preferably of rubber or other resilient material and its reduced upper end is further secured to the 35 shank 2 by means of a tubular retaining member 8.

10 designates a centering device loosely surrounding the vacuum cup 6 and consisting of metal or other suitable material. Said centering device 10 is of inverted cup-shaped 40 form and provided at its upper end with an opening 12 for the reception of the retaining member 8 and has a large opening 14 at its lower end for fitting over the valves of 45 internal combustion engines.

A coil spring 16 is interposed between a collar 18, fixed upon the shank 2, and the upper portion of the centering device 10 for 50 pressing the latter down on the cylinder block B and assisting in lifting the vacuum

cup 6 at intervals during the grinding operation.

In practice the pin for retaining the usual valve spring (not shown) in place is removed and the centering device 10 is placed over the 55 valve A and upon the top of the cylinder block B to center the vacuum cup 6 upon said valve. The vacuum cup 6 is then firmly pressed upon the valve A to exclude the air from the interior of said cup so that it will 60 be held to the valve by atmospheric pressure in the well-known way. The valve may then be rotated upon and raised from the seat C, as shown by Fig. 1, every few turns to change 65 its general position on said seat.

By yieldably mounting the centering device 10 upon the cup 6 and the retaining element 8, the tool is rendered flexible and the shank 2 may be moved to various angular positions with respect to the plane of the 70 vacuum cup 6 and the centering device 10, for obtaining the best results in the grinding operation. As the opening 14 in the lower portion of the centering cup 10 is but slightly larger than the diameter of the valve 75 A, it will coact with the latter in preventing the vacuum cup 10 from slipping laterally out of position on said valve during the grinding operation.

From the foregoing description it will be 80 understood that we have provided a valve grinder that is well adapted for the purpose intended and while we have shown one form of the invention we reserve all rights to such other forms and modifications as properly 85 fall within the spirit and scope of the invention as claimed.

Having thus described our invention, what we claim and desire to secure by Letters 90 Patent, is:

1. A valve grinder consisting of a shank, a vacuum cup mounted upon said shank, and a centering device loosely surrounding said vacuum cup to center the latter upon the valve and permit said shank to be moved to 95 various angular positions with respect to the plane of the vacuum cup and said centering device.

2. A valve grinder consisting of a shank, a vacuum cup mounted upon said shank, a 100

centering device loosely surrounding said vacuum cup and adapted to surround the valve being ground, and spring means pressing against said centering device and adapted 5 to lift the vacuum cup.

3. A valve grinder consisting of a shank, a vacuum cup mounted upon said shank, and an inverted cup-shaped centering device loosely surrounding said vacuum cup and 10 adapted to surround the valve being ground.

4. A valve grinder consisting of a shank provided at one end with a handle, a resilient vacuum cup mounted upon the other end of said shank, a centering element surrounding 15 said vacuum cup, and adapted to surround

the valve being ground, and spring means pressing against said centering element and adapted to lift the vacuum cup.

5. A valve grinder consisting of a shank, a resilient vacuum cup mounted upon one end 70 of said shank, an inverted cup-shaped centering element surrounding said vacuum cup and adapted to surround the valve being ground, a collar secured to the shank, and a coiled spring pressing at one end against said collar 75 and at its opposite end against said centering element.
